SHOE SEWING MACHINE

Cyril Harry James and Fred Ricks, Leicester, England, assignors to United Shoe Machinery Corporation, Flemington, N. J., a corporation of New Jersey

Application October 31, 1950, Serial No. 193,144
In Great Britain January 4, 1950

2 Claims. (Cl. 12—1)

1

This invention relates to improvements in machines for sewing shoes.

A method of shoe manufacture which enables a high quality "closed toe" and "closed heel" shoe and which simulates a slip-lasted shoe of the platform type, has recently been proposed. For this purpose a technique is employed somewhat similar to that used in the manufacture of Veldtschoen shoes. In accordance with the method referred to an upper is "pulled over" a last on a Veldtschoen Assembling Machine of the type disclosed in United States Letters Patent No. 1,996,103, granted April 2, 1935, upon application of Harold E. Elliott et al. and as modified in accordance with the disclosure of the complete specification of British Letters Patent No. 453,844. The upper of a Veldtschoen shoe then is lasted and has its marginal portion united with the marginal portion of a reinforced sock lining, to which has been "spotted" previously a relatively thick resilient sole member in the nature of a platform sole, a sewn seam conveniently having been inserted by a machine known in the shoe manufacturing trade as a No. 4 Rapid Stitching Machine and disclosed in United States Letters Patent No. 1,198,405 granted September 19, 1916, upon application of Arthur Bates. In the latter patent, the machine includes, in addition to the usual stitch forming devices, a gripper, operating in time relation to the sewing instrumentalities, for tensioning the upper and pulling it down to the last.

The stitching machine of the last-named patent may be provided with a knife fitted to the presser foot of the machine in such manner that it depends therefrom and enters the platform sole in a locality near the sewing point so that, as the work is fed past the sewing instrumentalities, the knife drags through the sole and forms a cut shaped in outline following closely that of the seam. In this way the stitches are pulled down into and through the cut and are set against the reinforced sock lining, portions of the sole lying outwardly of the seam line being trimmed off.

For advantageous use in carrying out the method above referred to, the stitching machine is provided with a guide for directing a platform wrapper or cover strip into a seam which unites the upper and sock lining. After the sewing operation the platform cover extends upwardly around the shoe with what will eventually be its outside surface lying adjacent the upper. The platform cover is later turned down to cover the edge of the sole member and is lasted under

2

the marginal portion of the sole member conveniently by means of a machine of the kind disclosed in United States Letters Patent No. 2,411,827, granted November 26, 1946, and No. 2,476,970, granted July 26, 1949, both upon application of Joseph Fossa. An outsole and shallow heel are then attached to the shoe bottom in a conventional manner.

With the arrangement above referred to it is difficult to cause the knife to cut into the sole to the proper depth without cutting into the sock lining. If the knife does not quite cut through the sole member it has been found that there is a tendency for the stitches, as they are set, to cut through the shallow remaining uncut portion but, in this case, with soles of fibrous or granular materials at least, portions of the material may become trapped under the stitches and, later, work out leaving the stitches loose.

It is one of the various objects of the present invention to provide a stitching machine having an upper tensioning gripper, as above referred to, with improved cutting means, so constructed and arranged that there is no danger of cutting into the reinforced sock lining when operating on a shoe of the kind above described.

There will be hereinafter described a convenient construction of machine provided by the invention and illustrative thereof, the illustrative machine being of the curved hook needle type disclosed in Patent No. 1,198,405 but, with the above objects in view, the usual presser foot is dispensed with, the machine being provided instead with a combined cutting device and presser foot block supporting a severing knife clamped to a notch in the block and having formed at a lower end thereof a fin projecting between adjacent layers of the materials and forming the presser foot of the machine to clamp the sock lining and upper together and to protect the sock lining from injury by the knife.

In preparing work for operation by the illustrative machine the marginal portion of the sole is not stuck to the marginal portion of the reinforced sock lining and the sole, at one point around its periphery, has a notch extending through its thickness at the starting position of the stitching operation. The work will be then presented to the machine in such manner that the knife of the combined cutting device and presser foot, is received in the notch in the sole while the fin extends beneath an adjacent portion of the margin of the sole between the sole and the reinforced sock lining and actually presses the latter with the upper materials and

platform wrapper against the work support of the machine. During operation of the machine the upper is tensioned by the usual gripper devices and the margin of the upper is secured to the margin of the sock lining, the peripheral portion of the sole being completely cut through by the knife, as the work is fed past the stitch forming devices at a location adjacent the seam line, the stitches as they are formed being pulled down through the cut and set tightly against the sock lining.

The platform wrapper or cover is subsequently turned down and lasted under the bottom face of the sole to cover the edge thereof. Those marginal portions of the upper, sock lining and wrapper, in the vicinity of the seam, which immediately after the stitching operation are in a somewhat outflanged condition will also be turned downwardly, and somewhat inwardly, with the downturned wrapper covering the other portions. In order to prevent the parts from bulging unduly outwardly beyond the desired outline of the shoe bottom (a condition which would be undesirable as detracting from the appearance of high class shoes) it is contemplated to set the knife above referred to, while being in the vicinity of the seam line, in a manner to cut through the sole member along a line following the seam but spaced inwardly (of the shoe bottom) a distance of some $\frac{1}{8}$ " from the actual seam line, thereby providing room to receive the portions of the upper, sock lining and wrapper adjacent the seam when the wrapper is turned down.

In using a stitching machine of the general kind disclosed in Patent No. 1,198,405, it is desirable to tip the shoe relatively to the path of movement of the needle to varying extents as the operation proceeds around the shoe, such tipping being most necessary when sewing along the inside of the shank (where the side of the last within the upper is usually markedly concave). Despite such tipping of the shoe to varying extents the marginal portions of the upper, reinforced sock lining and platform wrapper are held between the presser foot and the work support in substantially a fixed plane. In order to insure that the marginal portion of the platform sole also is maintained in a substantially fixed horizontal plane throughout the stitching operation and that the sole is cut at substantially a constant angle perpendicular to its tread surface all around the shoe, the illustrative machine hereinafter described is provided with a spring pressed collar slidably mounted for yielding movement along the blade of the knife and downwardly against the tread surface of the sole, which is uppermost during the stitching operation. The collar squeezing the marginal portion of the sole against the fin on the presser foot tends to hold the marginal portion of the sole in a substantially fixed plane during the stitching operation despite tipping of the shoe to varying extents as that operation proceeds around the shoe.

These and other features of the invention as hereinafter described and claimed will be apparent from consideration of the following detailed specification and accompanying drawings in which:

Fig. 1 is a side sectional elevation taken in a plane at the left of the operating devices in a machine embodying the features of the present invention;

Fig. 2 is a detailed view of a portion of the operating mechanism for the presser foot, showing

also a portion of the work support and wrapper strip guide;

Fig. 3 is a similar view of the work support, wrapper strip guide and operating devices showing a portion of a shoe located in operating position;

Fig. 4 is a plan view of the parts shown in Fig. 3;

Fig. 5 is a front view of the parts shown in Fig. 3;

Fig. 6 is a detailed view of a modified form of combined trimming knife and presser foot;

Fig. 7 is a detailed plan view of a clamping member employed on the modified form of presser foot shown in Fig. 6;

Fig. 8 is a perspective view of a platform sole and attached sock lining intended to be operated upon by the machine of the present invention, and;

Figs. 9, 10 and 11 are sectional views of a shoe showing successive stages of its construction up to its completion in Fig. 11.

The illustrated machine is generally similar to that of Patent No. 1,198,405 above referred to and is arranged for operation upon a Veldtschoen type of shoe. The machine is designed to last and secure simultaneously the parts of a shoe together and in the present form of the machine a shoe of the platform type is intended to be constructed simulating in many respects a shoe of the type normally known as "a slip lasted shoe."

Referring more particularly to Figs. 9 to 11 of the drawings the shoe is provided with a relatively resilient platform 12 having attached thereto a sock lining 14. The upper of the shoe is indicated at 16 surrounding a last 18 and attached to the sock lining 14 by thread stitches 20 passing also through one edge of a platform wrapper or cover strip 22.

The machine has a curved hook needle 24 and a curved awl 26 and other stitch forming devices arranged to form a lock stitch seam. The shoe is fed by the awl which is mounted on a feed slide 28. For lasting the upper the machine is provided with a lasting mechanism comprising a gripper having an upper jaw 30 and a lower jaw 32 actuated in timed relation with the stitch forming devices. The machine also is provided with a work support 34 and a presser foot of special construction arranged to cooperate in an advantageous manner with the platform sole 12 of the shoe. The presser foot is secured to a lever 36.

The platform sole 12 and the sock lining 14 are substantially the same as employed in the usual construction of a platform type slip lasted shoe except that instead of securing the sock lining and platform sole throughout their entire adjacent engaging surfaces their marginal portions are left free from their extreme edges inwardly along a line approximately a half inch from their edges. In addition the edge of the platform sole at one side approximately in line with the breast of the heel surface is provided with a notch 38 entering the edge substantially the same distance as the line limiting the attachment of the platform sole and sock lining. To secure the sock lining to the platform sole an adhesive of known composition is employed. With the platform sole and sock lining constructed in the manner indicated it is located on the tread surface of the last 18 about which the upper 16 is stretched and temporarily secured in place. The parts are then presented to the

machine which inserts the permanent fastening 20 and directs the wrapper strip 22 into the seam.

The seam 20 is directed in the machine by the engagement with the bulging last supported surface of the shoe upper 16, to conform with the shape of the last employed. After completing the seam the wrapper strip 22 is lasted over the edge of the platform sole and carried beneath the platform sole as shown in Fig. 11, covering the bottom edge of the platform sole and the folded under edges of the wrapper strip. An outsole 40 is attached to complete the shoe. In order to enable the wrapper strip to be lasted over the edge of the platform sole the edge of the sole is severed and trimmed off nearly to the line marking the inward limit of the free marginal portions between the platform sole and the sock lining, this trimming operation being accomplished simultaneously with the sewing. Thus, both the sewing and trimming are directed together in conformity with the shape of the last employed.

To insure cutting the platform sole entirely through without danger of injury to the sock lining, according to a feature of the invention, a knife is employed with a knife holder having a relatively thin fin or disk which enters between the free and unattached marginal portions of the platform sole and the sock lining, clamping the sock lining to the work support and guarding the sock lining against injury by the knife. The knife and fin constitute a separate attachment to the presser foot lever 24 replacing the regular presser foot employed on the machine of the Bates patent.

The knife and fin are illustrated more clearly in Figs. 3, 4 and 5 and are connected to a presser foot knife holder block 42. The knife holder block has a ribbed vertical clamping surface fitting the presser foot receiving end of the lever 36. The knife comprises a removable blade 44 clamped within a seat in a notch 45 (see Fig. 4) in the block 42 by a clamp member 46 having a lug engaging the knife blade 44 and a fulcrum rib 48 engaging a groove in the block 42. Between the blade engaging lug and the rib 48 the clamp member is perforated to receive a clamping screw 50 threaded into the block 42.

The fin is a portion of the block 42 and is indicated at 52 formed integrally with the block. The block 42 is provided with a rectangular recess into which the marginal portion of the platform sole 12 may ride. The fin 52 is beveled along its edges for easy movement between the platform sole and the sock lining and protects the lower cutting edge of the blade 44 against contact with the sock lining, the blade being engaged with the fin at its lower end.

At the start of a sewing operation on a shoe the shoe is presented to the machine in a manner to cause the blade to enter the notch 38 in the platform sole, the fin 52 projecting between and separating the platform sole and the sock lining. As soon as the machine is started the knife blade 44 begins to trim off a section of the marginal portion along the platform sole slightly in advance of the point of operation of the needle 24. Preferably the trimming knife block 42 is adjusted in its mounting on the lever 36 at a position where the knife will act approximately one sixteenth of an inch inside the line of the seam inserted by the needle. To enable the needle to operate without obstruction the trimmed off marginal portion of the platform sole is wedged rearwardly away from the main body of the

sole. The cutting edge of the knife blade is provided with a marked wedge shape to prevent interference between the material trimmed from the marginal portion of the sole and the operating parts in the machine, the knife wedging the trimmed material behind the needle path. The block 42 is provided with a guard plate 54 projecting in the direction of the completed stitches in a seam beyond the sewing point, the plate being inclined rearwardly of the machine sufficiently to enable the trimmed material of the sole to clear the operating parts of the machine behind the sewing point.

The trimmed marginal material of the platform sole 12 enters the recess in the block 42 above the fin 52 during operation of the machine but frequently the thickness of the sole is not sufficient to fill the entire recess. The clamping action of the machine, accordingly, is dependent upon the engagement of the fin 52 on the sock lining 14 so that the fin acts as a presser foot for clamping the sock lining, upper and edge portion of the wrapper strip against the work support 34.

To avoid any tendency for the clamped parts of the shoe to become distorted and to insure that the platform sole will be guided into a substantially perpendicular relationship to the knife blade 44 where the sole is of insufficient thickness to fill the recess in the block 42, the blade is surrounded by a spring pressed sliding collar 56, shown more clearly in Figs. 6 and 7. This collar is somewhat elongated along the seam line and receives the knife blade within an inside opening. The collar is bent upwardly and rounded at its ends to avoid digging into the tread surface of the platform sole along its central portion. The collar is formed with a pair of eyes within which project the inturned ends of a U-shaped wire spring 58 clamped by a set screw 60 along its central portion to the knife block 42.

The machine of the Bates patent is provided with a thread pull-off mechanism automatically adjusted to cause an amount of thread to be measured in accordance with the thickness of the work clamped between the presser foot and the work support. This pull-off mechanism also is employed in the present machine and is adjusted to insure automatic measurement of thread sufficient to sew material of thickness corresponding to the relative clamping position of the fin 52 on the knife block 42. However, the variation in thickness of the work operated upon in the illustrated machine is not so marked as when the entire thickness of an outsole also is being sewn. Also it is desirable to relieve the clamping pressure on the presser foot on the work while the work is being fed. For this purpose the presser foot actuating mechanism has been modified from that illustrated in the Bates patent so that a positive presser foot lifting movement is obtained during each sewing cycle. For this purpose the presser foot lever 36 which is fulcrumed on a shaft 62 is engaged at the rearward side of its fulcrum shaft by a set screw 64 carried by an angle plate 66 clamped to an actuating arm 68 rotatably mounted on the fulcrum shaft 62. The rearward end of the actuating arm 68 is connected to a short link 70 in turn connected to a cam actuated lever 72 having a roll 74 engaging a cam on a main sewing shaft 76 of the machine.

For directing the platform cover or wrapper to the sewing point an L-shaped guide 78 is pro-

vided secured to the awl carrying feed-slide 28. The guide 78 is disposed to apply the wrapper to the outflanged upper of the shoe in angularly bent relation, with the shorter arm of the angle contacting the upper and with the apex of the angle coinciding with the angle between the bulging side and the outflanged portion of the upper.

The nature and scope of the invention having been indicated and the particular embodiment having been described, what is claimed is:

1. A machine for sewing an upper to a sock lining attached intermediate its marginal portions to a platform sole, said machine having stitch forming devices and work clamping members comprising a work support, in combination with a presser foot and knife holder block formed with a notch, a knife removably clamped in the notch in the block for severing the unattached marginal portion of the platform sole during operation of the stitch forming devices and a fin 15 on the block engaged by the knife at one end of its cutting edge to clamp the sock lining and upper on the work support and to protect the cutting edge of the knife from contact with the sock lining.

2. A machine for sewing an upper to a sock lining attached intermediate its marginal portions to a platform sole, said machine having stitch

5 forming devices and work clamping members comprising a work support, in combination with a presser foot and knife holder block, a knife removably clamped on the block for severing the unattached marginal portion of the platform sole during operation of the stitch forming devices, a fin on the block engaged by the knife at one end of its cutting edge to clamp the sock lining against the work support and to protect 10 the cutting edge of the knife from contact with the sock lining, and a spring pressed collar movable along the knife to guide the platform sole into a substantially perpendicular relationship to the knife.
